CLAIM

The ornamental design for a filter basket for immersion coffee or tea brewing and cupping, as shown and described.

DESCRIPTION

FIG. 1 is a front perspective view of a first embodiment of a filter basket for immersion coffee or tea brewing and cupping;

FIG. 2 is a front isometric view of the filter basket for immersion coffee or tea brewing and cupping of FIG. 1; FIG. 3 is a side isometric view of the filter basket for immersion coffee or tea brewing and cupping of FIG. 1; FIG. 4 is a side view of the filter basket for immersion coffee or tea brewing and cupping of FIG. 1;

FIG. 5 is a bottom isometric view of the filter basket for immersion coffee or tea brewing and cupping of FIG. 1; FIG. 6 is a bottom view of the filter basket for immersion coffee or tea brewing and cupping of FIG. 1;

FIG. 7 is a top view of the filter basket for immersion coffee or tea brewing and cupping of FIG. 1; FIG. 8 is a front isometric view of a second embodiment of the filter basket for immersion coffee or tea brewing and cupping;

FIG. 9 is a bottom isometric view of the filter basket for immersion coffee or tea brewing and cupping of FIG. 8;

FIG. 10 is front isometric view of the filter basket for immersion coffee or tea brewing and cupping of FIG. 1, shown in a state of use; and,

FIG. 11 is a side view of the filter basket for immersion coffee or tea brewing and cupping of FIG. 1, shown in a state of use.

The broken lines show environment and form no part of the claimed design.
